BROACHING MACHINE

Frank C. Wilson, Arcade, N. Y., assignor to The Manufacturers and Traders Trust Company, Buffalo, N. Y., a corporation of New York, Jack A. Ahern and David D. Nash, both of Buffalo, N. Y., as executors of the estate of Kirke R. Wilson, deceased

Application May 9, 1950, Serial No. 160,889

6 Claims. (Cl. 90—33)

1

The improvements constituting this invention relate to hydraulic presses and provide a machine which combines the availability for all broaching operations, whether pushing or pulling, with the availability for all of the operations of an arbor press.

The improved press is characterized by a rectangular ram-connected operating frame which is available both for broaching and arbor press operations and is movable relatively to a stationary supporting frame including standard structural upright elements suitably connected, either cross bar of the operating frame serving for the operative connection of the broach accordingly as the broaching operation may be effected by pulling or pushing. The upper cross bar of the operating frame cooperates with a work supporting bed or platen in a push broaching operation and in any of the sundry arbor press operations. The lower cross bar of the operating frame cooperates with the platen in pull broaching operations.

The structural elements of the supporting frame may be unfinished, i. e. not machined, which is an advantage from the standpoint of manufacturing economy, in which case novel provision is made for insuring the exact rectilinear movements of the operating frame, notwithstanding any irregularities in the surface outline of the structural elements.

The improved press may also be a unit self-contained as to all essential operating features and, therefore, readily movable to any location on the floor of the shop which may be most convenient for the particular work to be performed.

In the accompanying drawings:

Figure 1 is a front perspective view of a hydraulic press in accordance with the invention.

Figure 2 is a front elevation of the operating frame with the associated ram elements, certain parts being shown in section.

Figure 3 is a partial rear elevation of the press.

Figure 4 is a top plan view thereof.

Figure 5 is a horizontal sectional view on the line 5—5 of Figure 1, parts being shown in elevation.

Figure 6 is a partial side elevation of the press.

Figure 7 is a vertical section on the line 7—7 of Figure 5 and is a central sectional projection of the part of the press shown in Figure 6.

Figure 8 is a detail section on the line 8—8 of Figure 7, looking in the direction of the arrows.

Figure 9 is a detail section on the line 9—9 of Figure 2, looking in the direction of the arrows.

Figure 10 is a detail vertical sectional view of

2

an element attached in the manner of a boss to the upper cross bar of the operating frame and which is available for the connection of the broach in a pushing operation and also for the application of pressure to the work in any of the uses of the press as an arbor press.

Figure 11 is a detail vertical section in the plane 11—11 of Figure 5.

Figure 12 is a detail horizontal section on the line 12—12 of Figure 7.

Figure 13 is a fragmentary elevation of one of the two similar plates connected to the lower part of the supporting frame and used in directing the flow of the coolant.

15 The supporting frame includes a pair of vertical uprights 1 and 1a which are preferably standard channel structural shapes with their flanges facing outward. The uprights are connected by transverse plates arranged in pairs, namely a lower pair 2 (Figure 7), an intermediate pair 3 and upper pairs 4 and 4a (Figure 2). The plates 2, 3, 4 and 4a are arranged adjacent the side edges of the uprights and are connected to their inner faces in any suitable manner, e. g. as by welding.

20 A bed plate or platen 5 extends between the uprights and is supported by the plates 3, being connected to them by screws 6 (Figure 5). The lower portion of the supporting frame fits within a box 7 which may be lagged to the floor and has its upper side partially open as at 8 (Figure 1) to accommodate the uprights. The uprights and one of the plates 2 may be suitably attached, e. g. as by welding, to the rear wall of the box 7 (Figure 7). The box extends forward for a suitable

30 distance and at the front of the press carries a removable cover plate 9 which provides a platform upon which the operator may stand. The portion of the box 7 at the front of the press may be conveniently used to hold various forms of broaching tools which may be supported upon racks 10. The platen 5 is provided with an opening 5a through which the broaching tool 11 may move either as a pull broach or a push broach.

35 The operating frame comprises upper and lower cross heads 12 and 13 and a pair of vertical tie rods 14 having shoulders which bear against the inner horizontal faces of the cross heads and are formed with threaded terminal extensions which project through openings in the cross heads and carry securing nuts. The cross head 12 is arranged above the platen 5 and the cross head 13 is arranged below it.

40 The operating frame is positively guided. For this purpose a pair of stationary vertical guide rods 15 is provided, one of which is carried by each

45 50

of the uprights adjacent its inner face. The guide rods 15 may be of any suitable cross sectional shape. As shown and preferred they are cylindrical. The platen 5 is formed with recesses 5b which are open to its end faces and which provide clearances to accommodate the tie rods 14 and the guide rods 15. The cross heads 12 and 13 are formed in their end faces with recesses 16 (Figures 3 and 5) to accommodate suitable bushings 16a which have a close fit upon the guide rods, conforming to them in outline and cross sectional dimensions.

In order to insure the proper alignment of the operating frame, notwithstanding any irregularities in outline of the inner faces of the uprights, each guide rod 15 carries adjustable aligning blocks 17 (Figure 2), preferably three in each instance, these being provided at or near the upper and lower ends of the guide rod and at an intermediate point. The blocks 17 are recessed to take over the guide rods and are rigidly secured to them by diametrically arranged screws 18 (Figures 7 and 8) tapped into the blocks. Each block 17 is connected to an upright by bolt and nut fastenings 19 arranged adjacent opposite sides of the guide rods. The blocks 17 carry screws 20 (Figures 7 and 8) which are tapped through the blocks and bear against the inner faces of the uprights. These screws are provided in pairs at each side of the blocks and the screws of each pair are located respectively above and below the bolt fastenings 19. The screws 20 are individually adjustable whereby as a series they will all bear upon the inner face of the adjacent upright 1 or 1a regardless of any surface irregularities. In effecting the adjustment of the screws 20 the nuts of the fastenings 19 are backed off and the screws 20 are then individually turned to engage their terminals with the inner face of the adjacent column. When the adjustment of the screws 20 has been effected the nuts of the fastenings 19 and the screws 20 are tightened against the blocks 17, thereby securely to attach the blocks to the uprights. The engagement of the screws 20 with the adjacent inner surfaces of the uprights in connection with the capacity for the individual adjustment of the several screws in order to compensate for surface irregularities insures that the blocks will, by means of the screws, have uniform multi-point bearing against the inner faces of the uprights, regardless of surface irregularities, while at the same time guide rods 15 will be maintained in exactly vertical and exactly parallel relation. In this way it is assured that the movements of the operating frame will be free from binding and will be truly rectilinear in a vertical path.

The operating frame is directly ram operated. In the embodiment shown the ram comprises a stationary cylinder 21 and a vertically movable piston rod 22. The ram is located above the operating frame and the rod 22 is directly and rigidly connected to the upper cross bar 12 by a suitable coupling 22a. The cylinder 21 is located between the cross plates of the pairs 4 and 4a and includes a top or cover plate 23. Horizontal supporting plates 24 and 25 for the cylinder 21 bridge the lower plates 4a of the upper pairs at their upper and lower sides. The cover plate 23 and the lower supporting plate 25 are connected by tie rods 26 which pass through openings in the upper supporting plate 24 and carry rigidly attached collars 27 for engagement with the upper face of this plate, thereby to provide

for the rigid support of the cylinder 21 by the plates 4a.

The piston rod 22 may be connected to the upper cross head 12 prior to the adjustment of the screws 20 in which case the nuts 27a at the ends of the tie rods 26 will not be tightened until the adjustment of the screws has been completed. The plate 24 preferably carries a pair of upright posts 28 which are located adjacent opposite sides of the cylinder 21. Between the bars 4 each post 28 carries a screw 29 (Figures 2 and 4) which bears against the cylinder 21 and similar screws 30 are tapped through the upper plates 4 and bear against the cylinder at points midway between the points of bearing of the screws 29. The purpose of the screws 29 and 30 is to make such adjustment of the cylinder 21 relatively to the piston 22 as will insure the perfect alignment of the cylinder and piston and the vertical movement of the piston in a true rectilinear path exactly aligned with the path of movement of the operating frame.

The source of the hydraulic power for the actuation of the ram and sundry associated features may have a remote location relatively to the press. The ideal, however, is a press which, as to the power elements, in a self-contained unit. The embodiment disclosed is a press so characterized.

The various parts involved in the hydraulic operation may be located in the box 7. It is preferred, however, that they be supported by a plate 31 (Figures 3 and 4) attached to the upper portions of flanges of the uprights, the attachment being effected preferably by welding. The various essential parts involved in the hydraulic operation and supported by the plate 31 are the reservoir 32 for the hydraulic liquid, the pump 33, the motor 34, the motor shaft 35, the pump shaft 36 and the coupling 37 between the shafts 35 and 36. Merely for the purpose of appearance a dummy panel 31a may be removably attached to the supporting frame in opposed relation to the plate 31.

The circuit flow connections between the reservoir and the ram and the features adjunctive to the circuit flow are standard and conventional.

The flow of the hydraulic liquid is controlled by a manually actuated valve 40 known in industrial manufacture as a "four-way" valve and having a by-passing feature. This valve may be of any suitable known construction, various forms of which are sold by industrial supply houses. It, therefore, requires no detailed illustration or description, it being deemed sufficient to identify the pipes involved in the circuit flow line and their connections to the valve and to other parts.

The valve 40 is mounted upon the upright 1a at its outer side. A pipe 38 connected to the output side of the pump extends upwardly and over the top of the supporting frame (Figures 3 and 4) and thence downwardly between the flanges of the upright 1a and at its lower end is connected to this valve. A by-pass pipe 41 is also connected to the valve 40 and to the bottom of the reservoir 32. The valve actuating handle 42 is pivoted and has three positions, namely raised, lowered, and intermediate or neutral. When the handle 42 is in neutral the liquid flows in an idle circuit through the pipe 41 and the reservoir 32. A pipe 43 extends from the valve 40 to the cover plate 23 of the cylinder 21. When the handle 42 is lowered the liquid under pressure flows through the pipe 43 into the top of the cylinder 21 and causes the ram piston 22 to move downward in

its operative stroke. Another pipe 44 extends from the valve 40 to the bottom of the cylinder 21 in such relation that when the handle 42 is raised the liquid under pressure flows through the pipe 44 into the cylinder 21 and causes the piston of the ram to move upward to its initial position, the liquid in the cylinder 21 above the piston flowing in reverse through the pipe 43 to the valve 40 and thence to the reservoir 32 through the by-pass pipe 41. Similarly, when the liquid enters the upper end of the cylinder 21 from the pipe 43 the liquid in the cylinder 21 below the piston flows in reverse through the pipe 44 to the valve 40 and thence to the reservoir 32 through the by-pass pipe 41. The liquid flows into the low pressure side of the pump through a pipe 45 which extends from the bottom of the reservoir 32.

The conventional adjunctive features are an air-cushion valve 46 arranged in the pipe 44 for the purpose of preventing a too sudden action of the piston in either direction of its movement; a pressure gauge 47 interposed in a line 48 which extends between the point of connection of the pipe 44 to the valve 40 and the casing of the valve 46; a pressure relief valve 49 connected to the pipe 38; a switch 50 mounted on the upright 1a and controlling the starting and stopping of the motor 34; and a reset box 51 also mounted on the upright and connected in the line which leads from the switch 50.

The lower cross head 13 of the operating frame carries at its upper side a centrally located socket 52 (Figures 2 and 7) which is provided at the upper end of a shank 53 extending through an opening in the cross head and held in fixed relation by a securing nut mounted on its lower end. The socket 52 accommodates the lower end of the broaching tool 11 as used for a pull broaching operation, the tool having a smooth surfaced lower extension 11a. The particular broaching tool selected, of course, depends on whether the broaching is to be internal or external, the tool selected for illustration being adapted for internal broaching. The socket 52 is formed with alining diametrical slots 54 and the lower extension 11a of the broaching tool is formed with a slot 55 which registers with the slots 54. The broaching tool is positively connected to the socket 52 by a key 56 which extends through the slots 54 and 55. When the broaching tool is to be connected to the socket 52 the operating frame is moved to its upper position. The extension 11a of the broaching tool is then inserted in the socket and the key 56 is inserted through the slots 54 and 55. The bars 3 are provided adjacent the platen 5 with recesses 57 (Figure 1) which afford clearances to enable the operator to insert the key 56 as a positive connection between the broaching tool and the socket 52.

The work piece W selected for illustration has an opening which is in alignment with the opening 5a in the platen. In the connection of the broaching tool to the socket 52 the extension 11a is initially passed through the opening in the work piece. The broaching operation is effected by the downward movement of the operating frame. Since the broaching tool operates in the opening of the work piece it will maintain the centering of the work piece upon the platen 5 during the broaching operation.

It will, of course, be understood that an indefinite number of forms of work pieces may be broached either internally or externally. For external broaching the work piece is secured to

the platen 5 by means of any well known clamping jig or other shop tool adapted for the purpose.

For push broaching operations the upper cross head 12 of the operating frame carries adjacent its lower face a centrally located boss 58 (Figures 3 and 10) which may have a flat tool engaging surface but which is preferably in the form of a socket as shown in Figure 10. The boss 58 is detachably connected to the cross head 12 and 10 may be removed when its use is not required. In the socketed form of the boss 58 the broaching tool is preferably positively connected by a key and slot arrangement similar to that above described for the connection of the broaching tool 15 to the socket 52. When the work conforms to the form W herein shown it is centered upon the platen relatively to the lower end of the broaching tool, the operating frame at such time being in an elevated position. Thereupon the operating frame is moved downward to effect the broaching operation.

If the boss 58 be flat surfaced the broaching tool may be initially positioned relatively to the work piece whereby when the operating frame 25 moves downward the boss 58 will engage the upper end of the broaching tool and push it through the work.

In the use of the machine as an arbor press any platen suitable for the particular work to be 30 performed may, if necessary, be substituted for the platen 5 as herein shown. In arbor press work the cross head 12 of the operating frame is utilized and if desired or necessary may (as shown by dot and dash lines in Figure 2) carry a downwardly projecting shank 59 which is alined with the ram piston rod 22 and performs the work that is performed by the downwardly projecting piston rod or plunger of the ram of the usual arbor press. Where the shank 59 is used 35 the cross head 12 may carry a detachably connected boss 60 which may be generally similar to the boss 58 as shown in Figure 10 and to which the shank 59 may be rigidly attached in any suitable manner.

In broaching work it is necessary to use a coolant. The drawings disclose a coolant circulating system incorporated with the press as a self-contained unit and which is integrated with the supporting frame construction and the box 7. 45 The box 7 which is of suitably greater width than the distance between the uprights includes a transverse partition 61 located in front of, and preferably spaced from, the front flanges of the uprights. The partition 61, the rear wall of the box 7, an end wall of the box 7 (at the left as shown in Figure 12), the web of the upright 1a, and a partition 62, coplanar with said web and located between it and the partition 61, provide a tank 63 which is at once a reservoir and a sump tank for the coolant. The rear wall of the box 7, the upright 1a, the partition 62, the partition 61 and the end wall of the box at the right (as shown in Figure 12) provide a chamber 64 in communication with the reservoir 63 by screened openings 65 (Figures 7 and 12) formed in the web of the upright 1a and the partition 62 near their lower ends. The circulation of the coolant is effected by a motor driven pump 66, the motor feature 67 of which is supported upon the top of the box 7 adjacent the outer side of the upright 1a and the pump feature 68 of which (Figure 6) is located in the chamber 64. The pump feature includes at its low pressure side an inlet 69 in open communication with the chamber 64 and at its outlet side 70 is in communication with a pipe 70 through which

the coolant is forced under suitable pressure. At its upper end the pipe 70 is connected to a flexible hose section 71 terminating in a nozzle 72 (Figures 1 and 5). The operator, grasping the section 71, directs the coolant discharged from the nozzle 72 against the broaching tool at a point adjacent and above the work piece W. The excess coolant flows upon the platen 5 and cascades from its transverse edges. The flow of the coolant as discharged by the nozzle 71 may be regulated by a valve 70a (Figures 1 and 6) fitted in the pipe 70 near its upper end.

The coolant circulating system includes dished panels 73 respectively adjacent the front and rear sides of the lower portion of the supporting frame and extending between the platen 5 and the box 7. The panels 73 are supported for quick detachment and for this purpose are provided with inturned marginal side flanges 74.

For the purpose of the attachment of the panels 73 the flanges of the uprights are provided with headed studs 75 (Figure 1) and below the studs with ogee shouldered brackets 76. The flanges 74 are provided near their upper ends with key-hole slots 77. In the attachment of the panels 73 the keyhole slots are articulated in the usual manner with the studs 74 and the panels are then lowered until the lower edges of the flanges 74 are behind the upwardly projecting portions of the brackets 76 and confined between them and the adjacent flanges of the uprights. When it is required that the panels be removed they are raised sufficiently for the larger ends of the key-hole slots to align with the heads of the studs 74 and for the lower edges of the flanges 74 to be above the upwardly projecting portions of the brackets 76, whereupon the panels are freely detachable.

The upper edges of the panels 73 (Figure 7) are spaced in suitable degree from the side faces of the platen 5 to provide clearance passages 78 through which the coolant cascades. On their inner faces the panels are provided (Figure 1) with downwardly converging strips 79 which extend from the upper edges of the panels at points beyond the ends of the platen 5 and are spaced at their lower ends to provide a coolant discharge passage 80. Either (or both) of the strips 79 may have at its lower end a downward vertical extension 81 to effect the issuance of the coolant in a concentrated stream. Suitably below the lower ends of the strips 79 the panels are each provided with a transverse strip 82 downwardly and inwardly inclined, the strips 82 projecting into the upper end of the reservoir 63. The coolant cascading from the side edges of the platen 5 is directed by the strips 79 to the passage 80 and thence falls upon the strips 82 by which it is directed into the reservoir 63. The coolant which follows the broaching tool through the opening 5a of the platen, of course, falls into the reservoir 63.

The coolant which is discharged into the reservoir 63 carries the chips and small metal particles resultant from the broaching operation. In order that the coolant as delivered by the nozzle 72 may be free of the chips and metal particles a basket 83 of wire screen mesh of suitable gage is supported within the reservoir 63 upon the upper faces of the cross plates 2. The coolant flows through the meshes of the screen mesh walls of the basket 83 into the reservoir 63 and the chips and other metal particles, which will not pass through the meshes, are retained in the basket as shown in Figure 7. When the accumulation

of chips and metal particles in the basket is in sufficient degree to require the cleaning of the basket the panels 73 are removed and the basket is lifted from the reservoir 63 and removed from the machine to be cleaned. In order that the basket may be conveniently so lifted and removed its end walls are provided with suitable bails 84.

The panels 73 are provided along their upper edges (Figures 7 and 13) with recesses 85 which register with the recesses 51 of the bars 3 to enable the fitting or removal of the key 56, the edges of the recesses 84 being preferably finished with beading 86 for the protection of the operator's hands in the application and removal of the key 56.

The motor feature 67 of the pump 66 is connected in circuit with the switch 50 whereby both motors 34 and 67 may be started and stopped at the same time, the circuit of the motor 67 being regulated by a micro-switch under the control of the valve handle 42 and being open when the valve handle is in its neutral position. Since the circuit features, including the micro-switch arrangement, are within the routine skill of any competent electrician, their illustration is deemed unnecessary. The circuit of the motor feature 67 also includes a standard reset box 87 which is supported by the upright 1a.

I claim:

1. A hydraulic press available selectively for push or pull broaching operations and arbor press operations comprising a supporting frame composed of parallel uprights and transverse plates connecting the uprights, a fixed horizontal platen mounted between the uprights, an operating frame comprising upper and lower cross heads and tie rods rigidly connecting the cross heads and maintaining them in spaced parallel relation, the lower cross head being arranged below the platen, and the upper cross head being arranged above the platen, either cross head being available for cooperation with a broaching tool, the upper cross head being used in cooperation with the platen for push broaching and arbor press operations and the lower cross head being used in cooperation with the platen for pull broaching, a pair of parallel vertical guide rods, each guide rod being connected for support to a corresponding upright and arranged adjacent its inner face, the cross heads having their end portions articulated with the guide rods for guiding cooperation, and a vertical hydraulic ram carried by the supporting frame and located outside the operating frame, the ram including a vertically movable element connected to one of the cross heads at a point central thereof and in alignment with the central vertical axis of the operating frame, thereby to effect the downward and upward movement of the operating frame.

2. A hydraulic press as set forth in claim 1 wherein the vertical guide rods each carry in fixed and spaced relation blocks for supporting connection to the uprights, each block carrying a plurality of individually adjustable screws, the terminals of which bear against the inner faces of the uprights, the adjustment of the screws in the blocks compensating for surface irregularities in the uprights and insuring that the guide rods are supported in truly vertical and parallel relation.

3. A hydraulic press as set forth in claim 1 wherein the platen is mounted upon a pair of transverse plates connecting the uprights, the lower cross head is provided with a centrally ar-

ranged socket for a broaching tool and the plates which support the platen are provided with recesses to enable the manual connection or disconnection of the broaching tool relatively to the socket.

4. A hydraulic press as set forth in claim 1 wherein a transverse connection between the uprights of the supporting frame is arranged above the operating frame, the stationary element of the ram is a fixed vertical cylinder connected for support to the transverse connection arranged above the operating frame, and means located suitably above said transverse connection is provided for adjusting the position of the cylinder with respect to a perpendicular axis in order to insure its accurate axial alinement with the central vertical axis of the operating frame.

5. A hydraulic press as set forth in claim 1 wherein the vertical guide rods each carry in fixed and spaced relation blocks for supporting connection with the uprights, each block carrying a plurality of individually adjustable screws, the terminals of which bear against the inner face of the uprights, the adjustment of the screws in the blocks compensating for surface irregularities in the uprights and insuring that the guide rods are supported in truly vertical and parallel relation, a transverse connection between the uprights of the supporting frame is arranged above the operating frames, the stationary element of the ram is a fixed vertical cylinder connected for support to the transverse connection arranged above the operating frame, and means located suitably above said transverse connection is provided for adjusting the position of the cyl- 35

inder with respect to a perpendicular axis in order to insure its axial alinement with the central vertical axis of the operating frame.

6. A hydraulic press as set forth in claim 1 wherein a lower pair of transverse plates connecting the uprights is arranged above the operating frame, an upper pair of transverse plates connecting the uprights is arranged above the lower pair, the stationary element of the ram is a fixed cylinder connected for support to, and extending upwardly from, the lower pair of transverse plates, fixed upright posts extend from the lower plates to the upper plates and between the upper plates and screws are tapped through the posts and through the plates of the upper pair for engagement with the cylinder in order to adjust its position with respect to a perpendicular axis, thereby to insure its accurate alinement with the central vertical axis of the operating frame.
